UNITED STATES PATENT OFFICE.

ELMER ELLSWORTH MACK, OF LOS GATOS, CALIFORNIA

PRUNE-GATHERER.

1,095,585.

Specification of Letters Patent.

Patented May 5, 1914.

Application filed December 9, 1913. Serial No. 805,553.

To all whom it may concern:

Be it known that I, ELMER ELLSWORTH MACK, a citizen of the United States, residing at Los Gatos, in the county of Santa Clara and State of California, have invented certain new and useful Improvements in Prune-Gatherers, of which the following is a specification.

My invention relates to prune gatherers, and the object thereof is to provide a prune gatherer which will not bruise or injure the prunes while being gathered from the ground. My prune gatherer is so formed that the points of the bent rods are bent downward and enter the ground below the prunes, thereby gathering the prunes into the receptacle formed by said bent rods without injury.

Another object is to combine with the bent rods as above described, a receptacle located rearward of the bent down points of the rods, said receptacle forming a pocket into which the prunes are gathered and retained until a sufficient quantity has been gathered, when the same are deposited in a box preparatory to being taken to a debris separator where the prunes are separated from any debris that might have been gathered therewith.

Broadly my invention consists in providing a prune gatherer wherein the ends of the bent rods have such curved points bending downward and projecting into the ground when the prune gatherer is being used, these curved points will extend below the ground surface while the receptacle rests upon the ground surface and is drawn along in this manner, the points passing under the prunes and depositing the ripe prunes into the receptacle without injury to the same, from which the prunes may be deposited in a box or other receptacle prepared for that purpose, and other means taken to separate the debris from the prunes.

For a full description of the invention and the merits thereof and also to acquire a knowledge of the details of construction of the means for effecting the result, reference is to be had to the following description and drawings hereto attached, in which,—

Figure 1 is a perspective view of my prune gatherer. Fig. 2 is a side elevation of my prune gatherer.

Corresponding and like parts are referred to in the following description and indicated

in all the views of the drawings by the same reference numerals.

The prune gatherer consists of a body portion or receptacle having a handle, the latter being of the required length to obviate stooping of the person when using the gatherer to pick up prunes and transfer them to a box or other receptacle.

The body portion of the prune gatherer comprises a longitudinal bar 1 made of any suitable material, and a plurality of bent rods shown at 2 connected at their upper ends to bar 1 in any substantial manner. These bent rods 2 may be made of round or flat steel wire of the proper length and strength required, bent and formed as shown in the drawings, having their lower ends 3 bent downward a distance so as to enter the ground surface below the prunes to be gathered into the receptacle formed by said bent rods 2, which prevents bruising or injuring the prunes while being gathered. Said bent rods 2 pass through and are supported and held in place by longitudinal bars 4, said longitudinal bars 4 are made of flat steel of the proper width, length and thickness, having a plurality of holes bored through the same of the proper size and of the required distance apart to receive the bent rods 2. Vertical rods 5 are shown at one end of said receptacle fastened to said bent rods 2, and are for the purpose of preventing the prunes from escaping from this end of the prune gatherer while said prunes are being gathered. At the other end of the prune gatherer is shown a wire screen door 6 held in place by hinges 7 and spring clasp 8. Fastened to the center of longitudinal bar 1 is handle bar 9 of the required length and thickness, having a handle at its outer end as shown at 10. On the under side of said handle 10 is fastened bell crank releasing lever 11. Attached to said lever 11 is wire cord 12 passing through eye-bolts 13, 14, and 15, and connecting with spring clasp 8.

The operation of my prune gatherer is as follows:—The ground under the trees is smoothed previous to the falling of the prunes, my invention is placed on the surface of the ground with curved points 3 entering the ground a distance below the surface thereof, and is thus drawn forward under the prunes, when the prunes will roll into the receptacle formed by said bent rods 2 without injury to the prunes. When there

are sufficient prunes gathered into the receptacle, the same are discharged into a box prepared for that purpose by raising the gatherer from the ground by handles 9 and 10, at the same time pressing bell crank releasing lever 11, which releases spring clasp 8 and allows door 6 to fly open and the prunes to run out into the box prepared for that purpose, when the prune gatherer is again brought to the ground the weight of the door 6 will close the same and spring clasp 8 locks the door 6 in place.

Having thus described my invention, what I claim as new and desire to secure by Letters Patent, is--

In a prune gatherer the combination of a longitudinal bar, a plurality of bent rods fastened thereto forming a receptacle, said bent rods having their outer ends bent outward a distance, longitudinal bars having a

plurality of holes bored therethrough to receive said bent rods and hold said bent rods forming said receptacle in position when fastened thereto, vertical rods fastened to one end of said bent rods forming said receptacle, a wire screen door hinged at the other end of said receptacle having a clasp to hold the same closed, a handle bar having a handle at its outer end, a bell crank releasing lever having a wire cord attached thereto, said cord passing through eye-bolts and connecting with spring clasp 8, substantially as shown and described.

In testimony whereof I affix my signature in the presence of two witnesses.

ELMER ELLSWORTH MACK.
